I claim the ornamental design for octagon weight, as shown and described.

DESCRIPTION

FIG. 1 is a front plan view of an octagon weight;
 FIG. 2 is a rear plan view thereof;
 FIG. 3 is a side elevational view of the octagon weight, all eight sides being a mirror image thereof;
 FIG. 4 is a rear side isometric view thereof;
 FIG. 5 is a front isometric view thereof;
 FIG. 6 is a front isometric view thereof; and,
 FIG. 7 is an isometric view of two octagon weights shown in a condition of use.
 The broken lines in the drawings are for the purpose of illustrating portions of the article that form no part of the claim.
